CLAIM

The ornamental design for eyewear for limited visual exposure, as shown and described.

DESCRIPTION

FIG. 1 is a front view of the eyewear for limited visual exposure shown as it may be worn by a person, wherein stipple on the lens indicates a limited transparency material; FIG. 2 is a front view of the eyewear for limited visual exposure;

FIG. 3 is a rear view of the eyewear for limited visual exposure;

FIG. 4 is a left side view of the eyewear for limited visual exposure

FIG. 5 is a right side view of the eyewear for limited visual exposure

FIG. 6 is a top view of the eyewear for limited visual exposure;

FIG. 7 is a bottom view of the eyewear for limited visual exposure;

FIG. 8 shows the eyewear for limited visual exposure as the straps may be unassembled from the lens; and,

FIG. 9 shows a rear view of the eyewear for limited visual exposure (as in FIG. 3), as a user may view the surrounding environment through the lens of the eyewear, wherein the environment seen through the lens of the eyewear is blurred relative to the detail of the environment seen outside of the lens of the eyewear; and

wherein the people and walls are shown as environment and do not form part of the design and therefore are shown with broken lines.
